(57) **CLAIM**

The ornamental design for a stuffed bear with hooded sweatshirt, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the U.S. Patent and Trademark Office patent file or records, but reserves all other copyright rights whatsoever.

FIG. 1 is a perspective view of a stuffed bear with hooded sweatshirt showing the new design;

FIG. 2 is a plan front view thereof;

FIG. 3 is a plan rear view thereof;

FIG. 4 is a plan right side view thereof;

FIG. 5 is a plan left side view thereof;

FIG. 6 is a plan top view thereof; and,

FIG. 7 is a bottom view thereof.

The broken line showing of the indicia on the sweatshirt is for illustrative purposes only, and forms no part of the claimed design.
